(57)

CLAIM

The ornamental design for a firearm as shown and described.

DESCRIPTION

FIG. 1 is a perspective view of the firearm;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a back view thereof; and,

FIG. 8 is another perspective view thereof.

The broken lines in the drawings disclose unclaimed portions of the firearm only and form no part of the claimed design.

1 Claim, 7 Drawing Sheets
